UNITED STATES PATENT OFFICE

FRANK E. PACKARD, OF BROCKTON, MASSACHUSETTS, ASSIGNOR TO GEO. E. KEITH COMPANY, OF CAMPELLO, MASSACHUSETTS, A CORPORATION OF MASSACHUSETTS

DESIGN FOR A SHOE

Application filed March 25, 1932. Serial No. 43,286. Term of patent 7 years.

To all whom it may concern:

Be it known that I, FRANK E. PACKARD, a citizen of the United States, residing at Brockton, in the county of Plymouth and State of Massachusetts, have invented a new, original, and ornamental Design for a Shoe, of which the following is a specification, reference being had to the accompanying drawing, forming part thereof.

The figure is a side elevation of a shoe, showing my new design, the side of the shoe opposite to that shown being substantially the same in appearance.

I claim:

The ornamental design for a shoe, as shown and described.

FRANK E. PACKARD.
